(57) **CLAIM**

The ornamental design for a housing for a charging case, as shown and described.

DESCRIPTION

FIG. 1 is a top, front perspective view of a housing for a charging case, showing my new design, shown in a closed configuration.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a cross-sectional front elevation view of the housing for a charging case of FIG. 1, taken in the direction of line 8-8 of FIG. 6.

FIG. 9 is a front perspective view of the housing for a charging case of FIG. 1, shown in an open configuration.

FIG. 10 is a front elevation view thereof.

FIG. 11 is a rear elevation view thereof.

FIG. 12 is a left side elevation view thereof.

FIG. 13 is a right side elevation view thereof.

FIG. 14 is a top plan view thereof; and,

FIG. 15 is a bottom plan view thereof.

In the drawings, the equal-length broken lines on the housing for a charging case form no part of the claimed design. The equal-length broken lines showing a lanyard and secondary item depict environmental subject matter only and form no part of the claimed design.
